To all whom it may concern:

Be it known that I, Wesley M. Cowen, a citizen of the United States and resident of New York, in the county of New York, State of New York, have invented a new, original, and ornamental Design for a Cigarette Caddy, of which the following is a specification, reference being had to the accompanying drawing, forming a part thereof, and of which:

Fig. 1 is a front elevational view of a cigarette caddy, showing my new design;

Fig. 2 is a side elevational view thereof;

Fig. 3 is a rear elevational view thereof;

Fig. 4 is a top plan view thereof, with the spring clip shown in open position; and

Fig. 5 is a bottom plan view thereof.
The broken line showing of a lighted cigarette in Fig. 2 is for illustrative purposes only.

I claim:

The ornamental design for a cigarette caddy, as shown and described.
